UNITED STATES PATENT OFFICE

127,194

DESIGN FOR A TEXTILE FABRIC

Jacques E. Maisch, New York, N. Y.

Application March 28, 1941, Serial No. 99,961

Term of patent 3½ years

To all whom it may concern:

Be it known that I, Jacques E. Maisch, a citizen of France, residing in the city of New York, county of New York, and State of New York, have invented a new, original, and ornamental Design for a Textile Fabric, of which the following is a specification, reference being had to the accompanying drawings, forming part thereof.

Fig. 1 is a plan view of a textile fabric showing my new design.

Fig. 2 is an enlarged view of a portion of the design for the purpose of bringing out more clearly certain of the details.

The design unit is contained between the dot and dash lines which unit is repeated in regular succession as indicated beyond the unit boundaries.

I claim:

The ornamental design for a textile fabric, as shown and described.

JACQUES E. MAISCH.
